UNITED STATES PATENT OFFICE.

JAKOB ZWICKY, OF LANGGASS, ST. GALL, SWITZERLAND.

TELESCOPE-TELEMETER.

1,204,229.

Specification of Letters Patent.

Patented Nov. 7, 1916.

Application filed October 30, 1911. Serial No. 657,530.

To all whom it may concern:

Be it known that I, JAKOB ZWICKY, a citizen of the Swiss Republic, residing at Langgass, St. Gall, Switzerland, have invented 5 certain new and useful Improvements in Telescop-Telemeters, of which the following is a specification.

The present invention relates to telescopes, and more particularly to telescopes arranged 10 in pairs, each of which is provided with a single cross wire, and each telescope being fixed to a horizontal pivot, these pivots having their axis at an acute angle with relation to each other, and perpendicularly to a 15 common vertical axis.

The apparatus is further provided with a 20 rod or bar which is placed horizontally at the point observed, and at an angle to the lines of observation, equal to 90° less the said acute angle, and is furnished with a scale, whereby distance may be determined.

A form of construction of the invention is illustrated in the drawing, in which—

Figure 1 illustrates an elevation of the 25 telescope instruments constructed in accordance with my invention; Fig. 2 is a plan view thereof; Fig. 3 is a plan view of the rod; Fig. 3^a is a side elevation of the rod; and Fig. 4 is a diagrammatic illustration of 30 the way in which the apparatus is used.

Referring now more specifically to the drawings, the telemeter illustrated is arranged on the head or top plate *a* of a stand, not shown, supporting a frame *b* consisting 35 of two standards. Between these standards, two telescopes *c* and *d* are arranged one above the other, and so mounted that their axes of oscillation and observation stand at an acute angle to each other, and when the 40 instrument is leveled, the point of intersection of the axes of oscillation and observation of the two telescopes are situated precisely vertically one above the other, and above the middle of the head plate *a*. The 45 effect of this is that when the two telescopes are oscillated, in the vertical direction, each moves in a vertical plane. Consequently in each telescope the vertically arranged wire running through the optical axis shows an 50 exact vertical line, that is to say, the lines of observation of the two telescopes meet exactly in the same place with a bar placed horizontally and at right angle to the line of sight of one of them.

The pivots *e* and *f* are each provided with a crank arm *g*, which arms are connected by

a link *h*, whereby when one telescope is oscillated about its axis, the other telescope will be oscillated correspondingly, and the relative position of the telescopes in their 60 vertical plane of oscillation will be maintained.

In combination with the telescopes, I employ a bar having a scale on both sides thereof, the scale having a zero mark indicated at *N*.

Since the bar *i* is to be used horizontally, I provide at each end thereof a level *k*, in order that the bar *i* may be accurately positioned. The bar *i* is further provided with 70 suitable markings which are viewed through the telescopes and in making an observation, the bar is positioned so that one of the zero marks of the scale indicated at *N* is directly in front of the instrument and lies somewhat in advance of the point of observation, and so that the bar forms a horizontal angle 75 with the line observed.

In order that the bar may be held precisely at the proper angle in relation to the 80 line of observation, the bar is provided with a detachable rod brace *m* that can be folded down or turned up and this brace *m* is provided with a sight *n*. Adjoining the zero mark is a mark *o*. The bar is held properly 85 if the sight *n*, the mark *o* and the center of the instrument lie in one line, which may be effected by suitable turning of the bar which can be indicated by the person using the instrument. The reference letter *p* indicates a 90 supporting rod placed vertically at the point observed, and on which a clamp *q* is arranged, whereby the bar may be positioned behind the zero point. This clamp is properly held in its place by suitable support- 95 ing means.

The operation of the device is as follows: The operation differs somewhat according to the length of bar used. The bar length as such depends upon the constant of the 100 device, which in turn is determined by the angle included by the two axes of the telescopes. The instrument is set up in the manner of setting up a theodolite or a transit, so that its vertical axis is perpendicularly over one terminal point of the horizontal range to be measured. The instrument is then placed in a horizontal position by manipulation of the three base screws, spirit levels provided for this purpose perpendicularly of the vertical axis, aiding in 105 this adjustment. The telemeter is then 110

ready. At the other terminus of the stretch to be measured, a helper sets up a pointing rod in a vertical position, aided therein by a spirit level. Next, that end of the bar which bears the "zero-mark" is attached to the vertical rod and secured thereto in any suitable manner. In the case of a short bar being used, the rod will readily support such bar in its laterally extending position.

10 If a longer bar is used, then a second helper must support the free end thereof. The bar is to extend horizontally, for which purpose a spirit level is provided. The bar is next brought into a position including an angle 15 with the line to be measured, which angle must be so much smaller than a right angle, as the angle between the two telescope axes amounts to. (Fig. 4.) For this purpose the holder *m* of the bar is raised and 20 the bar is turned about the rod as fulcrum until the sight in the holder appears in the line extending from the instrument to the mark *o* provided near the zero mark on the bar. The observer thus observes the mark 25 *o* directly in the sight *n*, when the bar has been swung into the proper position. Since the distance between mark *o* and zero mark *N* is equal to one-half the thickness of the pointing rod, the direction from the instrument to the mark coincides with that to the edge of the pointing rod, so that also the person holding the bar can "bring-in" the sight by respectively displacing the bar. If in this manner the bar is properly positioned, one of the telescopes is so adjusted 35 that its vertical hair appears in the zero mark of the bar, when the vertical hair of the other telescope will cover a certain mark on the bar, from which, then, the horizontal 40 distance sought can readily be read off.

What I claim, and desire to secure by Letters Patent is:—

1. The combination with a stand, and

Copies of this patent may be obtained for five cents each, by addressing the "Commissioner of Patents, Washington, D. C."

parallel standards thereon, of two horizontal pivots journaled in said standards one 45 above the other and at an acute angle to each other, and a telescope mounted intermediate its ends on each of said pivots.

2. The combination with a stand, and parallel standards thereon, of two horizontal pivots journaled in said standards one 50 above the other and at an acute angle to each other, a telescope mounted, intermediate its ends on each of said pivots, and means for connecting the telescopes to cause them to 55 oscillate simultaneously.

3. The combination with a stand, and parallel standards thereon, of two horizontal pivots journaled in said standards one 60 above the other and at an acute angle to each other, and a telescope mounted intermediate its ends on each of said pivots, a crank arm projecting from each pivot, and a link connecting the crank arms to cause the telescopes to oscillate simultaneously. 65

4. An instrument of the character described comprising a support, two telescopes mounted on the support to oscillate in vertical planes, and connections whereby they are caused to oscillate simultaneously, said 70 connections consisting of a pin secured to oscillate with each telescope, and a link connecting said pins.

5. A measuring instrument comprising a base, standards supported by the base, independent pivot members held between the standards, a telescope supported on each pivot and adapted to move therewith, and means connecting the pivots whereby the telescopes are moved simultaneously. 75 80

In testimony whereof I have affixed my signature, in presence of two witnesses.

JAKOB ZWICKY.
